UNITED STATES PATENT OFFICE.

GEORGE E. WARREN, OF SWAMPSOFT, MASSACHUSETTS, ASSIGNEE TO UNITED SHOE MACHINERY CORPORATION, OF PATERSON, NEW JERSEY, A CORPORATION OF NEW JERSEY.

ART OF HEELING SHOES.

Application filed August 3, 1923. Serial No. 655,541.

To all whom it may concern:

Be it known that I, GEORGE E. WARREN, a citizen of the United States, residing at Swampscott, in the county of Essex and State of Massachusetts, have invented certain Improvements in the Art of Heeling Shoes, of which the following description, in connection with the accompanying drawings, is a specification, like reference characters on the drawings indicating like parts in the several figures.

This invention relates to the art of heel- ing shoes, and particularly to methods of operating upon heels and parts thereof, comprising various steps and the order of their performance with a view to the accurate and economical preparation, attach- ment and finishing of multi-section heels.

The invention is herein shown as applied to the manufacture of men's shoes provided with multi-section heels. In such work it is common practice to apply to the heel seat a base, which may consist of one or two lifts, compressed to give it the necessary rigidity, and a cushion top section of rubber. These parts of the heel may be attached to the shoe successively by two sets of nails, or by single nailing, which consists in driving a single set of nails through the rubber top sec- 30 tion, the base and the heel seat and clinching inside the shoe. In order to obtain firm nailing of heels having compressible top sections, it is the general practice to use the method set forth in Standish Patent No. 35 1,288,253, granted Dec. 17, 1918, according to which the base is enough larger than the rubber top section to provide a marginal bearing for the Standish ring to press upon the relatively rigid base and produce a tight 40 joint between the base and the shoe sole. This margin, to provide a bearing for the ring, has commonly extended across the breast of the base, as well as around the curved periphery of the heel, and its pres- 45 ence necessitates breasting and scouring op- erations on the base after the heel is at- tached.

The breasting and scouring operations after the heel is attached require a high de- 50 gree of skill, consume a good deal of time, and often result in damage to the shank portion of the shoe sole. It is the object of the present invention to provide a method of operation which, when applied to this 55 part of the manufacture of a shoe, will in-

crease the speed of production, improve the accuracy of results and avoid all the loss which is at the present time suffered from damaged work.

There is relatively small importance in 60 pressure upon the base across the breast and, in its broader aspect, the novel method of the present invention provides for the production of a final surface upon the breast of a heel base prior to the attachment of the base to the shoe, attachment of the base and a top section to the shoe, either simulta- 65 neously or successively, with their breast faces in approximate alinement, and finish- 70 ing the breast of the top section to the breast surface which has already been pro- 75 vided upon the base. All danger of dam- age to the shoe by the knife of a heel breast- 80 ing machine is eliminated, as is also the dif- 85 ficult part of the heel breast scouring opera- 90 tion, that is, the scouring into the sharp cor- 95 ner formed by the shoe sole and the breast of the heel base. The breast face of the heel base can also be formed much more quickly and accurately before the base is 100 attached to the shoe, and by the use of suit- 105 able automatic machinery which is now ob- 110 tainable this operation may be performed in connection with the usual compressing operation at practically no labor cost and with the expenditure of no additional time.

In a preferred manner of practising the invention the heel base is compressed, breast- 115 ed, breast scoured if desired, and assem- 120 bled with a rubber or other top section with 125 the breast faces of the two sections in ap- 130 proximate alinement, preferably with the breast of the top section overhanging slight- 135 ly the breast of the base. The Standish 140 ring may be provided with gaging surfaces 145 to facilitate obtaining this relation. The heel breast is finished after attachment by 150 scouring the breast of the rubber top sec- 155 tion back to alinement with the previously 160 shaped breast of the base. This method has 165 these advantages:—The base is breasted 170 without danger of cutting into the shoe sole; the breast face may be accurately lo- 175 cated; the base may be used as a pattern to 180 which to scour the rubber top section; and 185 the rubber top section is not distorted. The steps may all be performed in the 190 order described to secure the utmost ad- 195 vantage in the practice of the method, but 200 it is within the scope of the invention to 205

omit certain of them or to change the order of their performance within certain limits, one of the most important of which is that the breast face of the base be produced prior 5 to the attachment of the base to the shoe, in order to avoid the difficulties incident to breasting and scouring the breast of the base after attachment.

One manner in which the method of the 10 present invention may be satisfactorily performed is illustrated in the accompanying drawings, in which

Fig. 1 shows a conventional rubber heel base in the rough;

Fig. 2 shows the same heel base after it has been compressed and breasted and the breast scoured.

Fig. 3 is a view in side elevation showing the heel base of Fig. 2 assembled with a 20 rubber top section;

Fig. 4 shows the assembled heel of Fig. 3 attached to a shoe; and

Fig. 5 shows the attached heel after the breast of the rubber section has been scoured 25 to the breast of the base section.

In practising the method of the present invention a heel base is first operated upon to produce a final surface upon part or all of its edge. The heel base shown in Fig. 1 30 is typical of a form of base which is in common use and consists of a lift 10 of leather or similar material having a rand 12 secured thereto. The edge of the rough heel base is often more or less uneven as illustrated in Fig. 1. As shown in Fig. 2, the breast face 14 of the heel base has been shaped and smoothed to the final form which it is to have in the finished shoe. This forming 35 may be effected in any suitable manner; for example, the base may be compressed and breasted, and the breast may be scoured in the usual manner with sand paper or similar abrasive material. While the most perfect results are secured by compressing, breasting and scouring the breast face 14, one or 40 more of these operations may, in some instances, be omitted or the order in which they are performed may be changed. For example, an article may be produced by compression alone, which is sufficiently perfect to permit it to be scoured directly without making the intermediate breasting cut, or a sufficiently perfect surface may be produced by the breasting knife to make it unnecessary to scour. Under some circumstances, it may be preferred to breast the heel base before it is compressed. Other possible variations will occur to those skilled 45 in the art, the essential feature being that the final breast surface which the heel base is to have in the finished shoe be formed before the base is attached to the shoe. It should be understood that the term "final surface," as used here and elsewhere in this 50 specification and the appended claims, means

that all cutting, scouring, or other forming operations have been performed, and does not necessarily imply that any of the so-called "finishing" operations, such as blacking or polishing, have or have not been performed. As will be readily perceived, the object which is being sought is to eliminate the breast surface forming operations after the attachment of the heel to the shoe.

The breasted base section is next attached 75 to the heel seat end of the shoe in any suitable manner, for example, by the usual method of nailing, together with the top section 16 of the heel. In the accompanying drawings the top section 16 is illustrated as 80 a rubber half heel of a type which is in common use. The heel base and the top section 16 are attached with their breast faces in approximate alinement but the breast of the top section preferably overhangs slightly, as 85 shown at 18, to provide for a subsequent scouring of the breast of the top section to cause it to form a smooth, continuous surface with the breast 14 of the base. Fig. 3 shows the base and top section assembled in 90 proper relation off the shoe. The heel thus assembled may be attached to the shoe at a single nailing but it is within the scope of the invention to assemble the top section and the base directly upon the shoe or first to attach the base to the shoe and then to attach the top section, as long as approximate alinement of the breast faces of the two sections 95 upon the shoe is secured.

The attached heel, as shown in Fig. 4, is 100 now ready for the operations of trimming the side edges of the base, scouring the said edges and scouring the breast of the top section. These operations may be performed in the order described or in any other convenient order. For example, the side edges of the base may be trimmed and scoured before the base is attached to the shoe, and the corresponding edges of the top section may be 105 scoured to the edges of the base in the same way as is done with the breast. An important advantage is derived from the fact that there is no operation to be performed upon the attached heel with a heel breasting knife, with its attendant difficulty in respect to 110 damaging the outsole 20; and that part of the heel breast which it is difficult to scour satisfactorily—namely, the breast face 14 of the heel base—has its final surface and does not have to be scoured on the shoe. The 115 scouring of the breast face of the top section 16 is easily and conveniently guided by the previously formed breast face 14 of the base and, if the two sections of the heel have been 120 assembled with a rather close approximation to alinement of their breast faces, only a very small amount of scouring of the breast of the rubber top section is required to produce a smooth, continuous breast face upon 125 the heel as a whole.

While the accompanying drawings show a heel with a rubber top section, it is to be understood that the improved method of the present invention is applicable to multi-section heels in which the top section is made of leather or any other material which can be scoured or otherwise formed into a continuation of the adjacent surface of the base section.

Having described the invention, what is claimed as new and desired to be secured by Letters Patent is:—

1. That improvement in the art of heelng shoes which comprises forming a final surface upon an edge of a heel base, assembling said base with a heel top section with corresponding edges of the two sections in approximate alinement, attaching the assembled heel to a shoe, and thereafter finishing the edge of the top section to the said final edge surface of the base.

2. That improvement in the art of heelng shoes which comprises forming a final surface upon an edge of a heel base, attaching the base and a heel top section to a shoe with corresponding edges of the two section in approximate alinement and thereafter forming the edge surface of the top section into a continuation of the corresponding edge surface of the base.

3. That improvement in the art of heelng shoes which comprises forming a final breast surface upon a heel base, attaching the base and a heel top section to a shoe with their breast faces in approximate alinement, and finishing the breast face of the top section to the said final breast surface of the base.

4. That improvement in the art of heelng shoes which comprises breastng a heel base, attaching said base and a heel top section to a shoe with their breast faces in approximate alinement, the breast face of the top overhanging slightly the breast face of the base, and forming the breast face of the top section into a continuation of the breast face of the base.

5. That improvement in the art of heelng

shoes which comprises compressing a heel base, breastng said heel base, attaching said base and a heel top section to a shoe with their breast faces in approximate alinement, and scouring the breast face of the top section to the breast face of the base.

6. That improvement in the art of heelng shoes which comprises forming a final breast surface upon a heel base, assembling said base with a heel top section with the breast faces of the two sections in approximate alinement, attaching the assembled heel to a shoe, and finishing the breast of the top section to the finished breast of the base.

7. That improvement in the art of heelng shoes which comprises compressing a heel base, breastng the said base, scouring the breast face of the base, assembling the base with a rubber top section with the breast faces of the base and top section in approximate alinement, the breast of the top section projecting slightly beyond the breast of the base, attaching the assembled heel to a shoe, and scouring the breast of the rubber section to the scoured breast face of the base.

8. That improvement in the art of heelng shoes which comprises compressing a heel base and forming a final, breast surface thereon, attaching said base and a rubber top section to a shoe with the breast faces of the base and top section in approximate alinement, and scouring the breast of the top section to the breast face of the base.

9. That improvement in the art of heelng shoes which comprises breastng a heel base, assembling with the breastng base a rubber top section with the breast faces of the base and top section in approximate alinement but with the breast of the top section extending slightly beyond that of the base, attaching the assembled heel to a shoe, and scouring the breast of the top section to the breast of the base section.

In testimony whereof I have signed my name to this specification.

GEORGE E. WARREN.
